UNITED STATES PATENT OFFICE.

JOHN ECKERT, OF MADISON, INDIANA.

DESIGN FOR A STOVE.

SPECIFICATION forming part of Design No. 34,553, dated May 21, 1901.

Application filed April 13, 1901. Serial No. 55,795. Term of patent 7 years.

To all whom it may concern:

Be it known that I, JOHN ECKERT, a citizen of the United States, residing at Madison, in the county of Jefferson and State of Indiana, 5 have invented and produced a new and original Design for Stoves; and I do hereby declare the following to be a full, clear, and exact description of the invention, such as will enable others skilled in the art to which it applies to make and use the same.

The drawing is a perspective view of a stove, showing my new design.

As shown in the drawing, the leading or material feature of my design consists in a body 15 each of whose sides is composed of a semi-cylindrical middle portion A, with its diameter upright and its axis horizontal, joined at its upper and lower edges to upright plane rectangular portions B C, the upper edges of 20 the portions B being connected by a plane rectangular horizontal top D, and the lower edges of the portions C being connected by a plane rectangular horizontal bottom E. The

ends of the sides, top, and bottom lie in parallel upright planes and are joined to plane end 25 portions F of a shape suitable to entirely close the ends of the stove. On the top D is a short cylindrical tubular section H. The front end F has a tubular projection F', inclined slightly upward. A tubular slip cover or door I fits 30 on this projection F', having a closed outer end provided with a handle i. Below the projection F' is another smaller tubular extension F². A tubular slip-cover K, with handle k, fits on over this projection F². 35

Bent legs L extend down from the bottom E. Having thus described my invention, what I claim is—

The design for a stove, substantially as herein shown and described. 40

In testimony whereof I affix my signature in presence of two witnesses.

JOHN ECKERT.
